US0D1096890S

(12) **United States Design Patent** (10) Patent No.: **US D1,096,890 S**
(45) Date of Patent: ** Oct. 7, 2025

(54) **CAMERA**

(71) Applicant: **SAM-DIMENSION GmbH**, Stuttgart (DE)

(72) Inventors: **Alexander Linn**, Stuttgart (DE); **Robin Mink**, Stuttgart (DE); **Ulrich Wagensommer**, Stuttgart (DE)

(73) Assignee: **SAM-DIMENSION GmbH**, Stuttgart (DE)

(**) Term: **15 Years**

(21) Appl. No.: **29/941,641**

(22) Filed: **May 10, 2024**

(30) **Foreign Application Priority Data**

Nov. 10, 2023 (EM) 015040361

(51) **LOC (15) Cl.** **16-01**

(52) **U.S. Cl.**

USPC **D16/210**; D16/200

(58) **Field of Classification Search**

USPC D16/200, 201, 202, 203, 204, 205, 206, D16/207, 208, 209, 210, 211, 212, 213, D16/214, 215, 216, 217, 218, 219, 220

CPC G03B 17/00; G03B 17/02; G03B 17/04; G03B 17/08; G03B 17/56; G03B 19/00; G03B 19/02; G03B 19/04; G03B 15/03; G03B 2219/02; G03B 2217/00; G03B 2217/002; H04N 23/50; H04N 23/51; H04N 23/54; H04N 23/55; H04N 23/62; H04N 23/63; H04N 7/141; H04N 7/142; H04N 7/147; H04N 7/18; H04N 7/15; H04N 7/152; H04N 7/181; H04N 7/183; H04N 5/2251; H04N 5/2252; H04N 5/2253; H04N 5/2254; H04N 2101/00
